UNITED STATES PATENT OFFICE.

HERMAN R. FREUND, OF BROOKLYN, NEW YORK, ASSIGNOR TO INTERTYPE CORPORATION, OF BROOKLYN, NEW YORK, A CORPORATION OF NEW YORK.

MATRIX FOR TYPOGRAPHICAL MACHINES.

Application filed October 19, 1921. Serial No. 508,654.

To all whom it may concern:

Be it known that I, HERMAN R. FREUND, a citizen of Germany, having declared my intention of becoming a citizen of the United

5 States, residing at Brooklyn, in the county of Kings and State of New York, have invented new and useful Improvements in Matrices for Typographical Machines, of which the following is a specification:

10 The present invention relates to improvements in character bearing matrices of the kind used in typographical machines and more particularly machines of the linotype class, substantially as shown and described 15 in U. S. Letters Patent No. 436,532, granted September 16, 1890, to O. Mergenthaler.

The primary object of this invention is to provide a novel and improved matrix adapted for the casting of italic character 20 type or type bars therefrom and which is capable of being handled with facility by ordinary typographical machines, the improved matrix in its preferred form being so constructed that it can be used successfully 25 and practically in typographical machines of the linotype class designed originally to use matrices of the kind ordinarily employed in the casting of roman character type.

Heretofore italic type for characters of 30 relatively small sizes has been obtained by using the ordinary commercial form of matrix comprising a flat straight rectangular body of uniform thickness, in the edge of which the italic character was impressed.

35 The italic type characters thus obtained were not truly italic in all instances, owing to the necessary distortion of certain of the characters to accommodate them to the limited rectangular character-receiving area of the matrix body, although such matrices could be used to some extent. However, as the range of use of typographical machines increased, demand was made for the production 40 of italic type characters of the relatively larger sizes, and it was found that the usual flat rectangular and commercial form of matrix could not be employed satisfactorily for italic characters of the larger sizes, because the distortion and defects 45 existing in the smaller size characters would be exaggerated and hence too prominent in the larger size characters.

Effort also has been made to produce a 50 matrix having offset portions to form an intermediate area to receive and conform

generally with the inclination required by the type characters of the italic style, as is evidenced by U. S. Letters Patent No. 630,396, granted on August 8, 1899, to Berne Nadaill, but in endeavoring to make practical 60 use of such a matrix, I discovered that many of the requirements arising from the use of such a matrix in typographical machines of the linotype class had not been provided for in the matrix as shown and described in the 65 patent, and I have succeeded in devising a matrix which overcomes the obstacles and difficulties which presented themselves, and moreover, the improved matrix is capable of use in typographical machines of the 70 linotype class and of the usual kind designed to use the ordinary commercial matrices bearing roman type characters. The improved matrix, furthermore, is capable of accommodating italic type characters in the larger, 75 as well as in the small sizes, the matrix, according to the present invention, being properly shaped to receive the inclined italic style character and provided with lugs or 80 ears which are so disposed relatively to the body of the matrix that they will function properly in the distribution of the matrices and they will also guide the matrices in passing into and through the magazine in which 85 they are stored.

The present invention also provides novel spacing means for use in conjunction with the improved matrices, whereby a line of matrices of the improved form may be filled out and locked by the operation of the usual 90 justifying means of the machine, and it provides filler pieces which enable the line of matrices to be carried through the machine and properly confined between the vise jaws and which also enable a mixed 95 line of italic and roman character matrices to be assembled and justified properly, preparatory to the casting of a type slug therefrom.

To these and other ends, the invention 100 consists in certain improvements and combinations and arrangements of parts, all as will be hereinafter more fully described, the features of novelty being pointed out particularly in the claims at the end of the 105 specification.

In the accompanying drawing:—

Figure 1 represents a composite or mixed line of italic and roman character matrices 110 justified and locked between the vise jaws

and in condition for the casting of a type bar or slug therefrom;

Figure 2 is a perspective view of a spacer modified in accordance with the present invention to accommodate an italic character matrix at one side thereof;

Figure 3 is a perspective view of a filler piece adapted for use in squaring the line at one side of an italic character matrix;

10 Figure 4 is a perspective view of the improved italic character matrix in its preferred form;

15 Figure 5 is a perspective view of a filler piece which is complementary with the filler piece shown in Figure 3 and is adapted for use in squaring the line at the opposite side of an italic character matrix;

20 Figure 6 represents a part of the upper end of the matrix magazine illustrating diagrammatically the manner in which the improved italic character matrices are received and guided while passing into and through the magazine in which they are adapted to be stored; and

25 Figure 7 represents a cross-section through the casting portion of a typographical machine of the linotype class, illustrating the manner in which the line of matrices is presented to the mold.

30 Similar parts are designated by the same reference characters in the several views.

Italic character matrices constructed in accordance with the present invention and the adjuncts provided by the present invention for use therewith may be employed in typographical machines of various kinds, although these matrices and their adjuncts are particularly applicable for use in typographical machines of the linotype class and 40 of the ordinary kind designed to employ the usual roman character matrices. The invention in its preferred embodiment is shown in the accompanying drawing and will be hereinafter described in detail, but it is to be understood that the invention is not restricted to the precise construction shown, as equivalent constructions are contemplated and these will be included within the scope of the claims.

50 In the present instance, 1 and 2 represent the vise jaw of a typographical machine of the linotype class, these vise jaws, as is well known, functioning in the usual way to confine the line of matrices in casting position in front of the usual mold 3, the vise jaws receiving the lines of matrices from the usual first elevator 4 in the usual way. In machines of this class, the faces of the vise jaws against which the ends of 55 the line abut, are parallel or substantially so to fit evenly against the ends of the line which, when made up of the usual roman character matrices, are square.

60 In the composite or mixed line shown in Figure 1, *m* designates italic character

matrices of the improved construction and bearing relatively small character faces, *M* designates the improved italic character matrices bearing relatively large character faces, and *M'* designates ordinary roman 70 character matrices assembled in the same line. *E* and *F* designate filler pieces adapted to be used at the ends of the line next to the italic character matrices to square these ends of the line and produce the proper fit 75 between them and the respective faces of the vise jaws, filler pieces being provided for each font of italic character matrices and being preferably stored in the same magazine therewith and releasable for delivery therefrom under control of the keyboard. The filler pieces *E* and *F* belonging to each font are complementary to one another so that they may be used either to square the line at any point in its length adjacent 80 to an italic character matrix, as, for example, is designated by the filler piece *E'*, or they may be used in pairs to form a spacer or quad between two words, as, for example, is illustrated by the filler pieces *E*² and *F*². 85 A solid or one-piece quad *G* may also be provided for use as a spacer between words, this quad being also preferably stored in the magazine containing the italic character bearing matrices, this quad or blank matrix 90 being of the same shape as the italic character bearing matrices belonging to the same font. A suitable number of wedges or expandable space bands *H* may be also provided for use when desired, this space band 100 being similar in its general construction to that ordinarily employed in conjunction with the usual roman character matrices, in that it comprises an upwardly movable wedge *H'* and a body *H*² having the usual supporting ears or lugs *H*³, but the body *H*² is formed with an offset portion *H*⁴ which is complementary to the side of the italic character matrix against which it fits. For example, a space band of this construction 105 may be used advantageously at the junction between a group of the ordinary roman character matrices *M'* and a group of italic character matrices *m*, as is shown in Figure 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

may be used to expand and justify the line in the ordinary way. Where the filler pieces are used in pairs, as is illustrated by the filler pieces designated E^2 and F^2 , the ordinary expandible space band H^5 with parallel faces could be used between these filler pieces to expand and justify the line.

Each italic character matrix, according to the present invention, comprises a body composed of upper and lower end portions M^2 and M^3 which are preferably of substantially rectangular form, as viewed edgewise, and an intermediate oblique connecting portion M^4 , the angle of the intermediate oblique portion M^4 corresponding with the inclination of the italic type character and providing an area of the correct form to receive the appropriate italic type character in its edge. Each italic character matrix is also provided with a pair of upper lugs or ears M^5 and a pair of lower lugs or ears M^6 . These upper and lower lugs or ears are located in vertical alinement, the upper lugs M^5 being preferably located immediately adjacent to one of the flat sides of the matrix body, but owing to the offset relation between the upper and lower portions M^2 and M^3 of the matrix body, the lower lugs or ears M^6 will be located at points offset inwardly from the flat side of the lower portion M^3 and toward the center thereof. This particular arrangement of the lugs or ears M^5 and M^6 is important where, as in the present instance, the italic character matrices are to be handled by the same mechanisms of the machine which ordinarily handle the usual roman character matrices. For example, in typographical machines of the linotype class, as is shown generally in the Mergenthaler patent above referred to, the distributor which returns the matrices to their respective channels in the magazine embodies three parallel screws, which are so related to one another that the forward sides of the threads of the three screws, are in alinement or in a common plane perpendicular to the axes of the screws, the threads of two of the screws engaging the upper lugs or ears, while the thread of the third screw engages one of the lower lugs or ears of the matrix and thereby advance each matrix along the distributor bar until the matrix reaches its respective magazine channel. By locating the lugs or ears M^5 and M^6 in alinement in the same vertical plane, it will be understood that these lugs or ears will be properly engaged by the threads of the distributor screws, and hence the matrices will be correctly advanced through the distributor. Also, the matrix storage magazine as commonly used in typographical machines of the linotype class, are provided with grooves or channels M^7 in their top and bottom walls, Figure 6 representing these channels as formed in the lower

wall of the usual magazine. By arranging the lugs or ears M^5 and M^6 in alinement in the same vertical plane, the italic character matrices in entering and passing through the usual magazine adapted for the handling of roman character matrices will be guided by the lugs or ears M^5 and M^6 in such a way that these matrices will travel in paths parallel with the upper and lower parallel portions M^2 and M^3 thereof, and hence they can be accommodated in the magazine without liability of the matrices in one channel catching against matrices in an adjacent channel.

It will be understood that the italic character bearing matrices and also the spacer pieces and the quad will be provided with the usual combination teeth for supporting them while traversing certain parts of the machine and during distribution, as is the case with the ordinary roman character matrices.

In constructing these italic character matrices for italic characters of different sizes, it is preferable to locate the tops of the characters in all cases with respect to an imaginary line 0—0 (Figure 1), this line corresponding or registering with the lower wall of the mold cavity 5, which wall is formed by the mold body 6 which, in machines of the linotype class, occupies an invariable or fixed position in the mold wheel or disk 7, the mold cap 8 which forms the upper wall of the mold cavity being commonly adjustable by the use of interchangeable liners interposed between it and the mold body, in order that the size of the mold cavity can be altered to cast type slugs of different body sizes. By using this line as a basis in locating the italic character faces of different sizes on the matrices, the correct registration between the matrices and the mold is always insured, notwithstanding variations in the sizes of the matrix characters and adjustments of the mold to cast type slugs of different body sizes.

By constructing the body of the matrix of upper and lower end portions connected by an intermediate oblique portion extending at an angle corresponding with the inclination of italic type characters, an area is provided on the edge of the matrix which is of the proper shape and inclination to receive a true impression of any italic character, and hence true italic type can be produced of the larger as well as the smaller sizes. By so locating the oblique character-bearing portion on each matrix that this portion begins at a level corresponding with the level of the mold body and terminates at a level corresponding with the height of the matrix character, the inclination of each matrix character, irrespective of the size thereof, is in definite relation to the constant or invariable edge of the mold and

hence correct fitting of the italic character matrices against one another and also correct spacing of the letters borne by the different matrices forming the line, are insured.

5 The disposition of the upper and lower supporting and guiding lugs or ears in alinement and in the same vertical plane, notwithstanding the relatively offset relation between the upper and lower end portions 10 of the matrix, enables italic character matrices to be used in machines of the linotype class as commonly designed to handle the ordinary roman character matrices, without requiring modifications or changes 15 in such machines, the successful distribution of the italic character matrices and their storage in the usual magazines in particular being rendered possible by the novel arrangement of these lugs or ears on the 20 obliquely offset body of the matrix.

I claim as my invention:—

1. A matrix for use in typographical machines comprising upper and lower portions offset relatively to one another and connected by an intermediate oblique character-bearing portion, in combination with upper and lower ears or lugs located in alinement with each other on the edges of the upper and lower portions of the matrix.

30 2. A matrix for use in line casting machines comprising a body having an oblique portion containing an italic type character and portions offset relatively to said oblique portion, said offset portions being provided with distributing and guiding ears vertically alined in a common plane.

3. A matrix for use in line casting machines comprising a body having a portion 40 thereof formed to receive an italic type character for reproduction and having lugs or ears for distribution of the matrices and guiding of the matrices while entering and passing through a magazine, the lugs at one portion of the matrix body being adjacent 45 to a flat side of the body and the lugs on another portion of the body being located at points removed from such side of the body and in the same vertical plane with the lugs first mentioned.

50 4. A matrix for use in a line casting machine comprising a body having an obliquely offset portion to receive an italic type character, one end of said obliquely offset portion being located at a level corresponding with the fixed level of the body of the mold of such machine, and the location of the other end of such obliquely offset portion corresponding with the size of the character which it bears.

60 5. A plurality of matrices for use in line casting machines, each matrix comprising a body having an oblique portion equal in dimensions to the particular size of the type character which it bears, said matrices bearing type characters of different sizes.

6. A matrix for use in typographical machines comprising a body having vertical portions and a portion adapted to occupy a position inclined to the vertical portions and bearing an italic type character, said vertical portions being provided with distributing and guiding lugs located in vertical alinement on the edges of the body.

70 7. A matrix for use in typographical machines of the linotype class comprising a body having a portion adapted to occupy a position inclined to the vertical and bearing an italic type character and distributing and guiding lugs adjacent to the upper and lower corners of the body, the sides of the 75 upper and lower lugs being alined vertically relatively to the inclined character bearing portion.

8. A matrix for use in typographical machines of the linotype class comprising a body having a character bearing portion adapted to occupy a position inclined to the vertical when assembled in a line, and distributing and guiding lugs adjacent to the upper and lower corners of the body which are alined in a common vertical plane when the matrix is so assembled.

90 9. A matrix for use in typographical machines comprising a body having a portion which is oblique to the longitudinal plane thereof and contains an italic type character, and distributing and guiding lugs on the edges of the body, said lugs being in longitudinal alinement with each other relatively to the body of the matrix.

95 10. A matrix for use in typographical machines comprising a body having upper and lower longitudinal portions which are offset relatively to the longitudinal plane of the body and an intermediate oblique connecting portion bearing an italic type character, and distributing and guiding lugs on the upper and lower portions of the body alined with each other in parallelism with the longitudinal plane of the matrix body.

100 11. A space band for use in conjunction with a matrix having an oblique character bearing portion, the space band comprising an elongated wedge and a part formed with an inclined portion to conform with the oblique character bearing portion of the matrix on one side and formed on its other side with a taper corresponding with that of the elongated wedge and being slidably attached thereto to operate, as the wedge 105 is advanced, to expand the width of the two parts of the space band.

110 In testimony whereof I have hereunto set my hand in presence of two subscribing witnesses.

HERMAN R. FREUND.
